Patented Apr. 19, 1921.

INVENTOR

P. H. DAVIS

BY Wm. Wallace White

ATTORNEY

UNITED STATES PATENT OFFICE.

PATRICK HENRY DAVIS, OF NEW YORK, N. Y., ASSIGNOR TO THE HAMILTON-LOW COMPANY, OF JERSEY CITY, NEW JERSEY, A CORPORATION OF NEW JERSEY.

VALVE.

1,375,215.

Specification of Letters Patent. Patented Apr. 19, 1921.

Application filed September 16, 1919. Serial No. 324,190.

To all whom it may concern:

Be it known that I, PATRICK HENRY DAVIS, a citizen of the United States, residing at 559 West 190th street, city, county, 5 and State of New York, have invented new and useful Improvements in Valves, of which the following is a specification.

My invention relates to valves and particularly to a valve adapted for use in a 10 dish washing machine, although it is to be understood that the invention is not limited to this adaptation.

An object of my invention is the provision of a pivoted or swinging valve which is 15 adjustable to compensate for wear or faulty construction, whereby a tight seating of the valve is insured.

I will describe one form of valve embodying my invention and will then point out 20 the novel features thereof in claims.

In the accompanying drawings, Figure 1 is a view showing in side elevation one form 25 of valve embodying my invention applied to a portion of a tank forming part of a dish washing machine.

Fig. 2 is a view showing in front elevation, the valve shown in Fig. 1 detached from the tank.

Fig. 3 is a view showing in bottom plan 30 the valve shown in the preceding views.

Fig. 4 is a detailed perspective view of the adjustable cam.

Referring specifically to the drawings in which similar reference characters refer to 35 similar parts of each of the several views, C designates generally a casing, including a top wall c formed with an opening 11, the wall of which is threaded to receive a pipe (not shown) through which water is admitted to the casing. c' designates the front 40 wall of the casing C, which, as shown in Fig. 2, is formed with a relatively large opening 12 and smaller openings for the reception of bolts 13 for securing the casing 45 to a wall T constituting a portion of the tank of a dish washing machine. The opening 12, which serves as the outlet opening of the valve casing, registers with a port 14 formed in the wall T, within which port 50 is seated a bushing having an annular shoulder 15 which provides a seat for a valve V. The opening 12 is of such shape as to permit free and unrestricted movement of the valve, as clearly shown in Fig. 2.

55 The valve V is substantially flat and of

ovate contour in outline, the pointed end thereof being provided upon its inner side with a collar 16 to receive the squared end of a stem S. As shown in Figs. 1 and 3, the casing C is provided with a rear wall 17 60 which is inclined downwardly and outwardly, and is formed with an opening of relatively large area through which the adjusting means and stem S are adapted to extend. This opening is covered by a plate 65 P secured to the casing by means of bolts 18. The plate P carries a sleeve 19 which loosely receives the stem S to permit rotary and longitudinal sliding movement of the stem therein and to form a substantial support for the stem when operating the valve. The outer end of the stem S projects beyond 70 the sleeve 19 a distance sufficient to allow the required longitudinal movement thereof and to receive a handle H which is fixed to 75 the stem by a collar 20 and a screw 21.

From the foregoing description it will be seen that the valve V is movable transversely of the port 14 to open and close the same by partially rotating the stem in one 80 direction or the other through the handle H. It will be understood that the walls of the opening 12 limit the movement of the valve V in either direction. By virtue of the longitudinal movement of the stem S 85 within the sleeve 19, the valve V can be adjusted laterally to compensate for wear or any inaccuracy in the construction of the parts of the valve, and yet secure the proper seating thereof. 90

To insure the tight seating of the valve, I provide the inner side thereof with a beveled lug 22 and a cam 23 is disposed in the path of the lug and adapted to force the same with the valve into tight engagement 95 with the seat 15 during movement of the valve to closed position. The lug 22 is fixed to the valve V, but the cam 23 is adjustable toward and away from the valve by means of a mounting comprising an extension 24 formed on the plate P which is bored longitudinally at three different points to slidably receive pegs or pins 25, 25' and 26. The pins 25 and 25' fit within suitable openings formed in the cam 23, and 100 act as guides and supporting means therefor, as will be understood. The pin 26 is independent of the cam 23 and serves to force the cam in the direction of the valve under the action of an adjusting screw 27 110

which is threadedly mounted in the extension 24 and abuts the inner end of the pin 26, as clearly shown in Fig. 3.

The operation of the valve may be briefly described as follows:

With the valve V in the open position as shown in dash lines in Fig. 2, the lug 22 does not engage the cam 23. However, during movement of the valve to closed position, the lug 22 engages the cam 23 just before the valve reaches its seat, whereby the surface of the lug 22 rides upon the inclined surface of the cam so that upon continued movement of the valve, the cam forces the latter into tight engagement with the shoulder 15. Should the valve become worn after continued use so that it fails to properly seat upon the bead 15, the cam 23 is moved inwardly to the desired position by means of the screw 27 until the valve is again thrown into tight engagement with its seat upon moving the same to closed position.

Although I have herein shown and described only one form of valve embodying my invention, it is to be understood that various changes and modifications may be made herein without departing from the spirit of the invention and the spirit and scope of the appended claims.

What I claim is:

1. A valve comprising a casing having in-

let and outlet openings therein, a valve controlling one of the openings and mounted for lateral and oscillatory movements, a beveled extension formed on said valve, a bored extension on said casing, a cam disposed in the path of movement of said beveled extension, pegs carried by the cam and slideable in said bored extension, a pin also slideable in said bored extension into contact with said cam and a screw threaded in the casing and engageable with said pin for adjusting the position of said cam.

2. A valve, comprising a casing having inlet and outlet openings therein, a valve controlling one of said openings and mounted for lateral and oscillatory movements, a beveled extension formed on said valve, a bored extension on said casing, a cam disposed in the path of movement of said beveled extension, said cam being mounted for bodily movement toward and from said bored extension, a pair of pegs carried by the cam and slideable in said bored extension, a pin also slideable in said extension and adapted to bear on said cam for limiting its movement in one direction, and means for adjusting said last pin.

In testimony whereof I have signed my name to this specification.

PATRICK HENRY DAVIS.
